GOLF CLUB CLEANING TOOL

Alfred A. Huber, Vermillion, Ohio

Application July 7, 1958, Serial No. 51,691

Term of patent 14 years

(Cl. D9—2)

I claim:

The ornamental design for a golf club cleaning tool, substantially as shown.
